(57) **CLAIM**

The ornamental design for a camera lens adapter, as shown and described.

DESCRIPTION

FIG. 1 is a perspective view of a lens adapter showing my new design;

FIG. 2 is a side elevational view of the lens adapter of FIG. 1;

FIG. 3 is an opposite side elevational view of the lens adapter of FIG. 1;

FIG. 4 is a top plan view of the lens adapter of FIG. 1;

FIG. 5 is a bottom plan view of the lens adapter of FIG. 1; FIG. 6 is a front elevational view of the lens adapter of FIG. 1;

FIG. 7 is a rear elevation view of the lens adapter of FIG. 1; FIG. 8 is a perspective view of the lens adapter of FIG. 1 in a position of use with an associated lens; and,

FIG. 9 is another perspective view of the lens adapter of FIG. 1 in a position of use with an associated lens and mobile device.
The broken lines in the drawings depict environmental subject matter that forms no part of the claimed design.

1 Claim, 6 Drawing Sheets
